OTTERSON.

EXAMINER'S ROOM.

NO. 11,112.

MARCH 25, 1879

UNITED STATES PATENT OFFICE.

JAMES P. S. OTTERSON, OF NASHUA, NEW HAMPSHIRE, ASSIGNOR OF ONE-HALF HIS RIGHT TO JOHN K. HOSFORD, OF SAME PLACE.

DESIGN FOR SHELF-BRACKETS.

Specification forming part of Design No. **11,112**, dated March 25, 1879; application filed February 24, 1879.
[Term of patent 3½ years.]

To all whom it may concern:

Be it known that I, JAMES P. S. OTTERSON, of the city of Nashua, county of Hillsborough, and State of New Hampshire, have invented a Design for Shelf-Brackets, of which the following is a specification:

The nature of my design is fully represented in the accompanying photographic illustration, to which reference is made.

A represents that part of the bracket to which the shelf is to be attached, or upon which it rests. B represents the portion affixed to the wall in any suitable way known to mechanics, which parts are the same as the ordinary brackets used for the purpose of supporting shelves and objects of like nature. The open-work between these two parts A and B consists of a series of interlaced circles, C C, and tangents D D D D, with their supports E and F, with the connecting ornament

G, all combining to form a brace or stiffening to support and strengthen the ribs A and B. These interlaced circles, tangents, and supports are paneled with sunk panels for the sake of saving material, as also being more ornamental than they would be if made plain. H is a corner-brace of similar design, which completes and perfects the uniformity of the whole.

What I claim as my invention is—

A design for a shelf-bracket in which the open ornamental work, which acts as a brace, is composed of interlaced circles and tangents, with supports and connecting ornaments, substantially as above described.

JAMES P. S. OTTERSON.
